(57) **ABSTRACT**

A protective barrier that will typically be installed beneath ceilings during construction work being performed on ceilings or roofs of buildings. The protective barrier can be comprised entirely of one material or of different materials connected by seams. Some or all of these materials can be designed to fail when contacted by water via dissolution, melting or through some other destructive process initiated by contact with water. This failure can create access points from the ceiling through the protective barrier to the area being protected by the barrier, which can allow water from a fire suppression system to reach a fire located below the protective barrier.

PROTECTIVE BARRIER AND METHOD FOR
ITS USECROSS REFERENCE TO RELATED
APPLICATIONS

This application claims benefit to provisional application No. 61/243,866, filed on Sep. 18, 2009, entitled, "WATER-SOLUBLE/DISSOLVABLE SEAMED PROTECTIVE BARRIER TO PREVENT THE CREATION OF FIRE HAZARDS IN A CONSTRUCTION AREA AND A METHOD FOR ITS USE," which is incorporated by reference herein in its entirety.

FIELD OF THE INVENTION

This device relates to protective barriers that are typically installed beneath ceilings during construction work being performed on ceilings or roofs of buildings. A protective barrier can comprise sections connected by seams. These seams or the entire protective barrier can be designed to fail when contacted by water, either by dissolution, melting or by some other destructive process. Failure of one or more of the seams can create access points from the ceiling through the protective barrier to the area being protected by the barrier.

BACKGROUND

Protective barriers, such as those described herein, prevent dust and debris from falling on floors, on people, or on equipment located below a ceiling or roof being repaired or constructed. In this way, the protective barrier protects from added costs from damage or injury resulting from this falling material and allows work to continue below the ceiling or roof. Such barriers are commonly constructed from polyethylene sheets or similar materials, which have proven to be durable, easy to work with, and inexpensive. However, a problem can arise with this type of protective barrier when it is installed below a fire suppression sprinkler system, which is often required in order to meet performance expectations. Such an installation can impair the flow of water from the fire suppression sprinkler system to a fire located beneath the protective barrier.

What is needed is a protective barrier that can perform its primary function of protecting people and property from falling dust and debris, but also has the capacity to allow water from a fire suppression sprinkler system to gain access to a fire located below the barrier.

SUMMARY OF THE INVENTION

It is an aspect of the present device to provide a protective barrier which can protect people and property from falling dust and debris, but also has the capacity to allow water from a fire suppression sprinkler system to gain access to a fire located below the barrier.

The above aspects can be obtained by a protective barrier that comprises at least two sections of waterproof material and a plurality of seams comprising a water soluble material attaching the at least two sections of waterproof material.

The above aspects can also be obtained by a protective barrier that comprises at least two sections of waterproof material and a plurality of seams comprising a material that reacts exothermically with water, the seams attaching the at least two sections of waterproof material.

The above aspects can also be obtained by a method that comprises providing a planar sheet comprising a material that

2

is either water soluble or reacts exothermically with water; and elevating the planar sheet above a floor and under a sprinkler system, wherein the planar sheet prevents dust or debris from reaching the floor.

These together with other aspects and advantages which will be subsequently apparent, reside in the details of construction and operation as more fully hereinafter described and claimed, reference being had to the accompanying drawings forming a part thereof, wherein like numerals refer to like parts throughout.

BRIEF DESCRIPTION OF THE DRAWINGS

Further features and advantages of the present device, as well as the structure and operation of various embodiments of the present device, will become apparent and more readily appreciated from the following description of the preferred embodiments, taken in conjunction with the accompanying drawings of which:

FIG. 1 is a schematic drawing of a protective barrier comprised of a water soluble material or a material that reacts exothermically with water according to an embodiment;

FIG. 2 is a schematic drawing of a protective barrier comprising water soluble seams, according to an embodiment;

FIG. 3 is a schematic drawing of a protective barrier comprising seams, which further comprise a material that can react exothermically with water, according to an embodiment;

FIG. 4 is a perspective drawing of a protective barrier installed beneath a fire suppression system;

FIG. 5 is a perspective drawing of a protective barrier installed beneath a fire suppression system, wherein a fire is located beneath the protective barrier and a sprinkler above the fire and protective barrier has been activated thereby releasing water; and

FIG. 6 is a perspective drawing of a protective barrier installed beneath a fire suppression system, wherein a seam has failed due to contact with water, creating an opening in the protective barrier and allowing water from a sprinkler to reach a fire.

DETAILED DESCRIPTION

This description of the exemplary embodiments is intended to be read in connection with the accompanying drawings, which are to be considered part of the entire written description. In the description, relative terms such as "lower," "upper," "horizontal," "vertical," "above," "below," "up," "down," "top" and "bottom" as well as derivative thereof (e.g., "horizontally," "downwardly," "upwardly," etc.) should be construed to refer to the orientation as then described or as shown in the drawing under discussion. These relative terms are for convenience of description and do not require that the apparatus be constructed or operated in a particular orientation. Terms concerning attachments, coupling and the like, such as "connected" and "interconnected," refer to a relationship wherein structures are secured or attached to one another either directly or indirectly through intervening structures, as well as both movable or rigid attachments or relationships, unless expressly described otherwise.

Reference will now be made in detail to the presently preferred embodiments of the invention, examples of which are illustrated in the accompanying drawings, wherein like reference numerals refer to like elements throughout.

FIG. 1 is a schematic drawing of a protective barrier 100 comprised of a water soluble material or a material that reacts exothermically with water according to an embodiment.

A protective barrier 100 can be comprised entirely of a water soluble polymer, which can prevent dust and debris from reaching a protected area when dry. This protective barrier can dissolve in full or in part when contacted by water allowing water from a fire suppression sprinkler system 101 to reach a fire 102 located below the protective barrier 100. The protective barrier 100 can be comprised of a polymer comprising polyvinyl alcohol or any other suitable water soluble material known to one of ordinary skill in the art.

A protective barrier 100 can also be comprised entirely of materials that react exothermically with water, which can prevent dust and debris from reaching a protected area when dry. This exothermic reaction can cause the protective barrier to melt in full or in part when contacted by water allowing water from a fire suppression sprinkler system 101 to reach a fire 102 located below the protective barrier 100. The protective barrier 100 can be comprised of a polymer or similar material further comprising magnesium metal or any other suitable material that react exothermically with water, that is known to one of ordinary skill in the art.

FIG. 2 is a schematic drawing of a protective barrier 200 comprising water soluble seams 201, according to an embodiment.

A protective barrier 200 comprising water soluble seams 201 can be comprised of sections 202 of standard, waterproof or water resistant material, such as polyethylene, vinyl or some other suitable material known to those with ordinary skill in the art of protective barriers. These sections 202 can be connected by seams 201 made from water soluble materials. Such seams 201 can comprise strips of water soluble materials which can be connected to the edges of the sections 202. These strips of water soluble material can be connected to the sections 202 by stitching, adhesives, glues, rivets, staples, or any other similar devices known to those with ordinary skill in the art (not pictured). Furthermore, the seams 201 can be totally comprised of water soluble stitchings, adhesives, glues, or similar connecting devices which are known to those of ordinary skill in the art (not pictured). Seams 201, comprising these water soluble materials, can dissolve upon contact with water allowing the sections 202 to fall to the floor or for openings to form between the sections 202 allowing water to pass by or through the protective barrier 200. In this way, the protective barrier 200 could allow water from a fire suppression system (not pictured) to reach a fire located below the barrier 200.

FIG. 3 is a schematic drawing of a protective barrier 300 comprising heat reactive seams 301, according to an embodiment.

A protective barrier 300 comprising heat reactive seams 301 can be comprised of sections 302 of standard, waterproof or water resistant material, such as polyethylene, vinyl or other suitable material known to those of ordinary skill in the art of protective barriers. These sections 302 can be connected by heat reactive seams 301 made from materials, or treated with chemicals that react exothermically with water to create heat sufficient to melt the heat reactive seams 301. This reactive material can be magnesium metal or any other material known to sufficiently react exothermically with water so that the heat reactive seams 301, comprising these heat reactive materials, can melt or otherwise disintegrate the heat reactive seams 301, comprising the protective barrier 300. This melting or disintegration can allow the sections 302 of the protective barrier to either fall to the floor or for openings to form between the sections 302 allowing water from a fire suppression sprinkler to pass by or through it 300.

The material(s) used for the seams in any of the embodiments described herein can cost more than the waterproof or

water resistant material used in the sections. Thus, by combining the seams and sections as described herein, a more cost effective barrier can be produced. Furthermore, in addition to the square checkerboard pattern illustrated in FIGS. 2-3, the sections and seams can be formed and connected using other shapes as well, such as triangles, diamonds, polygons, curves, arbitrary shapes, etc.

FIG. 4 is a perspective drawing of a protective barrier 400 installed beneath a fire suppression system.

The protective barrier 400 is located below a fire suppression system 405. The protective barrier 400 can comprise sections 402 of standard, waterproof or water resistant material, such as polyethylene, vinyl or other similar material known to those with ordinary skill in the art of protective barriers. These sections 402 can be connected by seams 401 made from water soluble materials, or materials that react exothermically with water and melt when contacted with water, or any other material that will cause the sections 402 to separate when exposed to water or fire. When dry, this protective barrier 400 can prevent dust and debris from reaching the protected area located beneath it.

FIG. 5 is a perspective drawing of a protective barrier 500 installed beneath a fire suppression system 505, wherein a fire 510 is located beneath the protective barrier 500 and a sprinkler 506 above the fire 510 and protective barrier 500 has been activated thereby releasing water 508.

Water 508 released by the sprinkler 506, which is part of the fire suppression system 505, contacts one or more seams 501 attaching sections of the protective barrier 500. This water 508 can dissolve seams 501 comprising water soluble materials, reducing their tensile strength and causing them to fail.

In an alternative embodiment, the entire protective barrier can be comprised of one or more water soluble materials. Water contacting any part of this protective barrier would cause the contacted part to dissolve resulting in openings in the protective barrier.

In another alternative embodiment, water 508 released by the sprinkler 506, contacts one or more seams 501 comprising the protective barrier 500. This water 508 can react exothermically with the seams 501 which can be made from materials such as magnesium metal, which react with water to create heat. This heat can cause the seams to melt or to sufficiently reduce their tensile strength to cause them to fail.

In another alternative embodiment, the entire protective barrier 500 can be comprised of materials that react exothermically with water. Water 508 contacting any part of this protective barrier 500 would cause the contacted part to melt or disintegrate resulting in openings in the protective barrier 500.

FIG. 6 is a perspective drawing of a protective barrier 600 installed beneath a fire suppression system 605, wherein a seam 601 has failed due to contact with water 608, creating an opening in the protective barrier 600 allowing water 608 from a sprinkler 606 to reach a fire 610.

In an alternative embodiment, wherein the entire protective barrier is made from water soluble materials, or materials which react exothermically with water, holes can be created in the barrier at any place where it is contacted by water.

Although the invention has been described in terms of exemplary embodiments, it is not limited thereto. Rather, the appended claims should be construed broadly, to include other variants and embodiments of the invention, which may be made by those skilled in the art without departing from the scope and range of equivalents of the invention.

What is claimed is:

1. A protective barrier, comprising:

At least one strip of water soluble materials; at least two sections of waterproof material; and a plurality of seams attaching the at least two sections of waterproof material and the at least one strip of water soluble material;

wherein the plurality of seams attaching the at least two sections of waterproof material and the at least one strip of water soluble material are formed by a third material.

2. The protective barrier as recited in claim 1,

wherein when the barrier is suspended in air and exposed to water, the at least one strip of water soluble materials dissolves causing the at least two sections of waterproof material to be released.

3. The protective barrier as recited in claim 1, wherein the strip of water soluble material is a polyvinyl alcohol-containing polymer.

4. The protective barrier as recited in claim 1, wherein the sections of waterproof material are comprised of a polymer.

5. The protective barrier as recited in claim 1, wherein the seams are located along edges of the at least two sections of waterproof material and the at least one strip of water soluble material.

6. The protective barrier as recited in claim 1, wherein the third material is not water soluble.

7. The protective barrier as recited in claim 6, wherein when the barrier is suspended in air and exposed to water, the at least one strip of water soluble material dissolves causing the at least two sections of waterproof material to be released.

8. The protective barrier as recited in claim 6, wherein the strip of water soluble material is a polyvinyl alcohol-containing polymer.

9. The protective barrier as recited in claim 6, wherein the sections of waterproof material are comprised of a polymer.

10. The protective barrier as recited in claim 6, wherein the seams are located along edges of the at least two sections of waterproof material and the at least one strip of water soluble material.

11. A method for using a protective barrier, the method comprising:

providing a planar sheet comprising:

at least one strip of water soluble materials; at least two sections of waterproof material; and a plurality of seams attaching the at least two sections of waterproof material;

wherein the said seams are attached to the said sections of waterproof material by at least one strip of water soluble materials;

and

elevating the planar sheet above a floor and under a sprinkler system,

wherein the planar sheet prevents dust or debris from reaching the floor.

12. The method as recited in claim 11, wherein the planar sheet comprises at least two seams of the material and strips of water soluble materials connecting sections of a waterproof substance.

13. The method as recited in claim 12, further comprising: a fire starting below the planar sheet causing the sprinkler system to emit water; and causing an interaction between the water and the strips of water soluble materials which causes the seams to break permitting the water to reach the floor.

14. The method as recited in claim 12, wherein the waterproof substance is a polymer.

15. The method as recited in claim 11, further comprising: a fire starting below the planar sheet causing the sprinkler system to emit water; and causing an interaction between the water and the strips of water soluble materials which permits the water to reach the floor.

16. The method as recited in claim 11, wherein the material comprises polyvinyl alcohol containing polymer.

17. The method as recited in claim 11, wherein the material comprises magnesium metal.

18. A protective barrier, comprising: at least two sections of waterproof material; and one or more seams attaching the at least two sections of waterproof material to form a planar sheet, wherein the one or more seams attaching the at least two sections of waterproof material are formed by a water soluble stitching, and wherein the two sections connected by one or more seams are located within the same plane.

19. The protective barrier as recited in claim 18, wherein when the barrier is suspended in air and exposed to water, at least some of the water soluble stitching dissolves causing the at least two sections of waterproof material to be released.

20. The protective barrier as recited in claim 18, wherein the water soluble stitching is a polyvinyl alcohol-containing polymer.

21. The protective barrier as recited in claim 18, wherein the at least two sections of waterproof material are comprised of a polymer.

22. The protective barrier as recited in claim 18, wherein the one or more seams are located along edges of the at least two sections of waterproof material.

23. A protective barrier apparatus, comprising: a planar sheet comprising 4 sections of waterproof material arranged 2 sections by 2 sections; and for each of the 4 sections, seams attaching the respective section to all of its adjacent sections of the 4 sections, wherein the 4 sections of the planar sheet are configured to lie flat,

wherein the seams are formed using a water soluble stitching configured to dissolve upon contact with water.

24. The apparatus as recited in claim 23, wherein the 4 sections are rectangular in shape.

25. The apparatus as recited in claim 23, wherein the 4 sections are each squares.

26. The apparatus as recited in claim 23, further comprising a sprinkler positioned above the planar sheet.
